UNITED STATES PATENT OFFICE.

HERBERT H. DREW, OF WATERTOWN, WISCONSIN.

TABLE SLIDE.

Application filed December 22, 1924. Serial No. 757,521.

To all whom it may concern:

Be it known that I, HERBERT H. DREW, a citizen of the United States, and resident of Watertown, in the county of Jefferson 5 and State of Wisconsin, have invented certain new and useful Improvements in Table Slides; and I do hereby declare that the following is a full, clear, and exact description thereof.

10 This invention relates to table slides.

In extension tables as heretofore constructed, it has been the uniform practice to provide lap blocks mounted within the grooves in the slides to limit the extension 15 of the slide. It has also been the practice to provide lap blocks of different lengths which were mounted within the grooves between the slides, so as to provide tables which had different extensions. When it 20 became necessary to change the extension of a table, extensive operations had to be employed to accomplish this result. For example, the slides had to be detached from the permanent leaves and moved apart in 25 order to expose the lap block and permit their removal. Thereafter, the outer slides were again attached to the leaves after new lap blocks had been positioned within the grooves.

30 This invention is designed to provide a slide for an extension table in which the outer slide members are permanently rigidly secured to the permanent leaves, in which the lap blocks are dispensed with, and in 35 which means are carried by the slide members which initially limit the extension of the table but which may be readily removed without removing either of the outer slide members from the permanent leaves, thus 40 materially simplifying the operation of changing the extension of the table.

In more detail, objects of this invention are to provide an extension slide in which 45 grooves or similar members are provided in the center slide member, and in which removable pins, such as threaded members, are carried by the outer slide members and normally fit within the grooves so that the pins may be readily removed when a greater 50 extension is desired without detaching either of the outer slide members from the permanent leaves.

An embodiment of the invention is shown in the accompanying drawings, in which:—

55 Figure 1 is a view from the under side of a table showing it in closed position and

showing the device adjusted for minimum extension.

Figure 2 is a view corresponding to Figure 1 showing the table extended. 60

Figure 3 is a view corresponding to Figure 2 showing the device adjusted for maximum extension.

Figure 4 is an enlarged transverse sectional view on the line 4—4 of Figure 1. 65

Referring to the drawings, it will be seen that a pair of outer slide members 1 and 2 are rigidly and permanently secured to the permanent leaves 3 and 4 of the extension table. An intermediate or center slide member 5 is positioned between the outer slide members and is slidably joined thereto in any suitable manner as for instance by means of the rollers 6' and end blocks 7, as shown in detail in Figure 4. 70

The center slide member 5 is provided with elongated slots 6 on opposite sides thereof and these slots, it will be noted, are provided with closed ends. The outer slide members are provided with removable pins 8 which are normally slidably set within the respective grooves. Preferably screws 8 are used for these pins and are threaded into the outer slide members 1 and 2, as clearly 80 shown in Figure 4, suitable recesses being 85 provided for their heads. The inner ends of the screws slidably fit the grooves 6 under normal conditions, and thus limit the extension of the table. For example, when the screws are in position, as shown in Figure 90 2, the table is adapted for one standard length of extension. If it is desired to alter this table and adapt it for a greater extension, it is merely necessary to remove the screw 8 and thus permit the table to be 95 extended to its greatest amount, the end blocks 7 contacting in the usual manner and preventing further extension.

It will be seen that the tedious and relatively difficult operation of detaching the 100 outer slides from the permanent leaves is wholly avoided by this invention, and a greater extension may be secured in a very simple manner by merely removing the screws 8. When it is considered that the 105 outer slides are usually not only securely fastened to the permanent leaves by screws or similar members but also glued either directly or through an intermediate block to such leaves it becomes at once apparent that 110 an alteration of the extension of the finished table is a relatively difficult matter and calls

for extensive operations. This invention overcomes these defects and permits a dealer to carry a small number of tables in stock having a given extension, and to quickly 5 change the tables to a greater extension, and it is thus apparent that the dealer is not required to carry a large stock of tables having different extensions.

Although the invention has been described 10 in considerable detail, it is to be understood that the invention may be variously embodied and is, therefore, to be limited only as claimed.

I claim:

- 15 1. A table slide comprising a central member and a pair of outer members mounted on opposite sides of said central member, said central member and said outer members having cooperating end blocks determining the maximum extension of the said slide, 20 said central member having a groove on each side provided with a closed end, and pins removably carried by each of said outer mem-

bers, and extending into said grooves and adapted to temporarily limit the extension 25 of the slide to a value less than its maximum extension, as defined by the end blocks.

2. A slide for an extension table comprising a central member and a pair of outer members, means slidably connecting said members, said central member having a pair of slots therein provided with closed outer ends, a pin carried by each of said outer members and adapted to operate in the corresponding slot and controlling the extension of said slide, said pins being removable to permit a greater extension of said slide, and end blocks carried by said outer members and said intermediate members and determining the maximum extension of said slide.

In testimony that I claim the foregoing I have hereunto set my hand at Watertown, in the county of Jefferson and State of Wisconsin.

HERBERT H. DREW.
